of Nevada

Application August 2, 1940, Serial No. 350,010

10 Claims. (Cl. 103—46)

This invention relates to fluid operated pumps for wells, and more particularly to a single-acting pump of such type.

This invention is an improvement over the device disclosed in my Patent No. 2,081,220, issued May 25, 1937, to which reference is hereby made.

Fluid operated pumps are of particular utility in producing oil from wells, and, consequently, the present invention will be described in connection with such use, although it is to be understood that my invention is susceptible of other and different uses and that I do not intend to be limited by the specific use of the embodiment described herein.

In the fluid operated pump art, hydraulic pumps adapted to pump from deep wells are normally complicated in construction, such as the device described in my said Patent No. 2,081,220, requiring many parts and being expensive to manufacture. By reason of the relatively complicated construction of such prior art devices, the relatively high cost of such a pump prohibits its use in oil wells in which the production is very low, commonly termed "stripper wells" in the art. It is therefore a primary object of my present invention to provide a hydraulic pump having a materially simplified construction so that the same can be economically operated in wells of low productivity.

It is a further object of my invention to provide a hydraulic pump of very small diameter so that it may be used in well tubing of small diameter, thus reducing the cost of well tubing for a well installation. Such an object has been impractical to accomplish with prior art devices, due to the relatively high minimum practical limits of diameter thereof, as the complexity of such prior art pumps and the practical manufacturing considerations involved therein have normally required external diameters of at least two inches. By using my present construction, I am able to provide a deep well pump having a maximum diameter of one and one-quarter inches or even less at less cost than has formerly been the case.

I have further discovered that where only a small well production is possible, for example less than fifteen barrels of oil per day, it is impractical to use the ordinary type of hydraulic pump in which the motor and pump pistons are of relatively large diameter, because for such use the pump is required to be operated very slowly to maintain the pump production below the normal productivity of the well. Obviously, if the pump production is greater than the normal well pro-

ductivity, the pump will soon reduce the level of fluid in the well to a point at which it is below the pump intake, thus causing the pump to pump merely air or gas, which is undesirable, and therefore if a hydraulic pump of the prior art type normally intended to produce a high capacity is used, it must be slowed down substantially to insure production of the desired low capacity. When a reciprocating hydraulic pump is slowed down materially below the rate of reciprocation for which it has been designed, many disadvantages occur, chief of which is the tendency for the pump pistons to hesitate at the ends of their strokes, causing jerky operation, high stresses, and other difficulties, which are particularly apparent if the pump is being used to pump well oil or other relatively viscous fluid. This is normally caused by faulty valve action when the valves are operated at low speed. My present invention is further intended to obviate these disadvantages by providing a hydraulic pump of small capacity in which the pistons thereof are reciprocated at a speed sufficiently high to give smooth operation without any tendency to hesitating at the ends of their strokes.

Still another object of my invention is to provide a single-acting hydraulic pump including a reciprocating pump piston in which the pumping is accomplished on the upstroke of the pump piston and the downstroke of the pump piston is insured by the application of operating fluid under high pressure thereto independently of the pressure exerted by the column of pumped fluid.

Other objects and advantages of my invention will be evident from the following specification and the drawings, which are for the purpose of illustration only, and in which:

Fig. 1 is a diagrammatic view of my pump unit for the purpose of clearly illustrating the general construction thereof.

Fig. 2 is a vertical sectional view of the upper portion of my invention.

Fig. 3 is a vertical sectional view of the central part of my device, extending downwardly from the bottom of Fig. 2.

Fig. 4 is a vertical sectional view of the lower part of my device, extending downwardly from the lower end of Fig. 3.

Fig. 5 is an enlarged cross-sectional view taken on the line 5—5 of Fig. 3.

Fig. 6 is an enlarged cross-sectional view taken on the line 6—6 of Fig. 3.

Fig. 7 is an enlarged cross-sectional view taken on the line 7—7 of Fig. 3.

Fig. 8 is an enlarged cross-sectional view taken on the line 8—8 of Fig. 4.

Fig. 9 is an enlarged cross-sectional view taken on the line 9—9 of Fig. 4.

Fig. 10 is an enlarged cross-sectional view taken on the line 10—10 of Fig. 4.

Referring to the drawings, I show the lower end of a production tubing 15 which is normally disposed in a well so that the lower end thereof is materially below the normal level of fluid in the well, the production unit being provided at its lower end with a conical seat 16. Suspended within the production tubing 15 on power tubing 17 is a fluid operated pump unit 18.

At the upper end of the fluid operated pump 18, there is provided a tubular valve housing 19 having a minor bore 20 and a major bore 21. Secured in the lower end of the major bore 21, as by shrink fitting or otherwise, is a valve sleeve 22 formed so as to provide an annular space 23 therearound between the valve sleeve and the major bore, the space being adapted to receive a slidable valve member 24 having a major portion 25 and a minor portion 26, the major portion fitting into the annular space 23 and the minor portion fitting into the minor bore 20 of the valve housing 19. Formed in the valve housing 19 are a plurality of radially disposed upper exhaust ports 27 communicating with the upper end of the major bore 21, and also connected with the upper portion of the major bore by an annular recess 28 is a longitudinal fluid passage 29 extending downwardly to the lower end of the valve housing 19. Also formed in the valve housing 19 is a longitudinal discharge passage 30 communicating between the lower end of the valve housing and a discharge port 31.

The valve member 24 is provided with a plurality of radially disposed intake ports 33 communicating through a spiral groove 34 formed in the inner surface of the valve member with a counterbored recess 35 also formed therein, which in turn communicates through a passage 36 formed in the lower portion of the valve member with the bottom of the valve member. Formed in the valve sleeve 22 are a plurality of radially disposed upper ports 37, a plurality of radially disposed lower ports 38, and a plurality of radially disposed intermediate ports 39, the purpose of which will be described hereinafter. The lower ports 38 communicate through an annular channel connecting the same formed in the valve sleeve 22 and an opening 40 in the lower end of the valve housing 19 with the discharge passage 30. Also provided in the valve housing 19 is a port 30a communicating between the passage 30 and the upper intake ports 33.

Threaded to the lower end of the valve housing 19 is a tubular motor barrel 42 provided therein with a liner 43, the liner being fluted as shown in Fig. 6 to provide longitudinal fluid passages 44 between the motor barrel and the liner. The upper end of the liner 43 abuts against a spacer member 45, the upper end of which in turn abuts against the lower end of the valve housing 19 and the valve sleeve 22. The spacer member 45 is provided with a bore 46 within which extends the lower end of the valve sleeve 22, and is provided with a counterbored portion 47 at its lower end. The spacer member 45 is provided with a longitudinal passage 48 communicating at its upper end with the discharge passage 30 and communicating at its lower end with an annular recess 49 formed in the lower end of the spacer member. Although only one

passage 48 and one upper discharge port 31 are shown, it will be understood that additional passages 48 may be annularly disposed in the spacer member 45 and that additional discharge ports 31 may be provided as desired. The lower portion of the spacer member 45 has a reduced diameter so as to provide a fluid space 50 between the spacer member and the tubular motor barrel 42, the upper end of which communicates through a groove 51 formed in the spacer member with the fluid passage 29 of the valve housing 19. The lower end of the fluid space 50 communicates directly with the longitudinal passages 44 formed between the motor barrel 42 and the liner 43.

The lower end of the motor barrel 42 is threaded to a pump housing 55, the upper end of which telescopes into the motor barrel and rigidly abuts against the lower end of the liner 43. Formed in the upper end of the pump housing 55, which constitutes the lower end of the motor cylinder, are fluid ports 56 communicating between the interior of the pump housing and the longitudinal fluid passages 44 through an annular recess 57 formed in the outer surface of the pump housing. As will be noted, the internal diameter of the pump housing 55 is, in the embodiment shown, the same as the internal diameter of the liner 43. The lower end of the pump housing 55 is threaded to a seat plug 58 having a beveled seat 59 formed on the lower end thereof adapted to seat in the conical seat 16 of the production tubing 15. An annular seat ring 60 formed of lead, rubber, or other suitable material, is provided in the beveled seat 59 so as to form a fluid-tight joint between the seat plug 58 and the conical seat 16 of the production tubing 15. The seat plug 58 is provided with an axial bore 61 having a valve seat ring 62 provided at the upper end thereof on which is adapted to seat a ball valve member 63 normally held in seated engagement with the valve seat ring 62 by a spider 64 held in engagement therewith by a compression spring 65 disposed between the spider and a valve cage 66, these valve parts constituting a standing valve means 62a of my invention. The lower end of the axial bore 61 communicates through an opening 67 formed in the lower end of the production tubing 15 with the fluid in the well to be pumped.

Provided in the liner 43 is a motor piston 68 having an axial fluid passage 69 therethrough, the upper end of the piston being counterbored to rigidly receive a head element 70 having a central passage 71 communicating with the axial fluid passage 69 and also communicating through horizontal openings 72 formed in the head element with the annular recess 49 of the spacer member 45. Suitable piston rings 73 are provided on the outer face of the motor piston 68 so as to form a sliding fluid-tight fit between the motor piston and the interior of the liner 43. Threaded into the head element 70 is an upper piston rod element 74 which extends upwardly through the valve sleeve 22 and the valve housing 19 into the power tubing 17, making a fluid-tight fit with the valve sleeve. The piston rod element 74 is provided with a plurality of lower grooves 75 formed around its outer surface and a plurality of upper grooves 76 also formed therein, for a purpose to be described hereinafter.

Connected to or preferably formed integral with the motor piston 68 is a central piston rod element 78 of smaller diameter than the motor piston, the lower end of which forms a pump

plunger 80, being slidably received in a pump liner 81 rigidly fixed in the pump housing 55 and having suitable packing rings 82 in the upper end thereof adapted to form a fluid-tight seal with the pump plunger 80. As shown, the pump plunger 80 is of the same external diameter as the central piston rod element 78 and slightly smaller than the motor piston 68, thus forming a differential acting pump in the construction shown. It will be apparent to one skilled in the art, however, that the size relation between the diameters of the motor piston 68 and pump plunger 80 may be varied as desired to meet any condition found in a particular well installation without departing from the spirit of my invention.

The pump plunger 80 includes what is known in the art as a travelling valve mechanism 83 comprising a tubular valve seat member 84 on the seat of which a ball valve member 85 is adapted to be normally engaged by a spider element 86 held in engagement therewith by a spring 87 engaging a working valve cage 88, as is understood in the art.

In operation, my invention operates as a single-acting pump in which well fluid is pumped from the well only on the upstroke of the pump plunger 80. With the parts shown as illustrated in the drawings, the motor piston 68 and the pump plunger 80 are in their uppermost positions, and the valve member 24 is in its lowermost position. With the parts so positioned, both the upper and lower faces of the motor piston 68 are exposed to the relatively low pressure of the column of pumped fluid in the production tubing 15, the upper face of the motor piston being at all times in open fluid communication with the interior of the production tubing through the annular recess 49, the longitudinal passage 48, the discharge passage 30, and the discharge port 31, the lower face of the motor piston being in communication with the interior of the production tubing through the fluid ports 56, the annular recess 57, the longitudinal fluid passages 44, the fluid space 50, the groove 51, the fluid passage 29, the upper end of the major bore 21, and the upper exhaust ports 27. Consequently, the fluid pressure exerted on the upper and lower faces of the motor piston 68 will be equal, and the upper end of the major portion 25 of the valve member 24 will be open to the relatively low pressure of the pumped fluid through the exhaust ports 27.

The power tubing 17 is at all times filled with operating fluid under relatively high pressure, conveyed downwardly therethrough to the fluid operated pump unit 18 from a suitable source of high pressure fluid (not shown), and it will be noted that the upper piston rod element 74 is at all times subjected to the pressure exerted by the operating fluid in the power tubing. Consequently, with the parts shown as positioned in the drawings, the pressure of the operating fluid exerted on the upper piston rod element 74 will cause the same together with the motor piston 68 and the pump plunger 80 connected thereto to move downwardly, thus producing the downstroke of the piston and plunger. As the pump plunger 80 moves downwardly, well fluid trapped above the standing valve mechanism 62a in the pump sleeve 81 will cause the ball valve member 85 of the travelling valve mechanism 83 to move off the seat to permit the well fluid to pass upwardly into the axial fluid passage 69 to fill the same with well fluid and to fill the space in the liner 43

above the motor piston 68. Some fluid from above the standing valve mechanism 62a may also be displaced upwardly through the passage 48. During the downstroke of the motor piston 68, the valve member 24 will remain in the position shown in Figs. 1 and 2, because any high pressure operating fluid leaking downwardly around the upper piston rod 74 will be exhausted through intake ports 33, the port 30a, the discharge passage 30, and the discharge port 31, into the column of pumped fluid, thus preventing operating fluid from reaching the lower end of the valve member 24 during the major part of the downstroke of the motor piston 68.

As the upper piston rod element 74 nears the lower end of its stroke, the upper grooves 76 formed at the top thereof will communicate with the upper ports 31 formed in the valve sleeve 22 to permit operating fluid under high pressure to flow from the power tubing 17 downwardly through the valve housing 19, the upper grooves 76 on the upper piston rod element 74, the upper ports 31, the counterbored recess 35, and the passage 36, to the lower end of the valve member 24. Although the upper end of the valve member 24 is at all times exposed to the high pressure of the operating fluid in the power tubing 17, due to the fact that the area of the lower end thereof is considerably greater than the area of the upper end thereof, and the upper end of the major portion 25 of the valve member is always open to the exhaust pressure in the column of pumped fluid, through the ports 27, when the high pressure fluid communication is opened as described to the lower end of the valve member, it will cause the same to move upwardly until the major portion 25 thereof engages the upper end of the major bore 21 of the valve housing 19. As soon as the valve member 24 starts its upward movement, the major portion 25 thereof soon covers the annular recess 28 to close communication between the fluid passage 29 and the exhaust ports 27. As the valve member 24 nears the upper end of its stroke, the intake ports 33 therein will register with the annular recess 28, thus opening fluid communication between the fluid passage 29 and the operating fluid under high pressure in the power tubing 17 through the upper end of the valve housing 19. Operating fluid under high pressure will then flow through the intake ports 33, the annular recess 28, the fluid passage 29, the groove 51, the fluid space 50, the longitudinal fluid passages 44, the fluid ports 56, into the lower end of the liner 43 so as to apply operating fluid under high pressure to the lower face of the motor piston 68. This causes the motor piston 68 to perform its upstroke carrying with it the central piston rod element 78 and the pump plunger 80 attached to the lower end thereof. During the upward movement of the pump plunger 80, the travelling valve mechanism 83 will be closed, and the well fluid above the motor piston 68 will be raised and discharged through the annular recess 49, the longitudinal passage 48, and the discharge port 31, into the interior of the production tubing 15. Upward movement of the pump plunger 80 produces a suction therebelow in the pump sleeve 81, causing the standing valve mechanism 62a to open to permit a fresh supply of well fluid to flow into the pump sleeve through the axial bore 51 and the opening 61.

As the upper piston rod element 74 approaches its uppermost position, the lower grooves 75 therein bridge the intermediate ports 39 and the lower ports 38 so as to afford fluid communication

between the lower end of the valve member 24 and the relatively low pressure fluid in the discharge passage 30 through the intermediate ports 39, the lower ports 38, the grooves 15, the discharge port 40, and the discharge passage 30. This reduces the pressure beneath the valve member 24 to the pressure of the pumped fluid in the production tubing 15, which is materially below the pressure of the operating fluid in the power tubing 17, and the pressure of the operating fluid in the power tubing acting on the upper end of the valve member causes the same to move downwardly to the position shown in Fig. 2, thus again opening the lower face of the motor piston 68 to the column of pumped fluid in the production tubing as described hereinabove.

Since the difference in area between the lower end of the motor piston 68 and the pump plunger 80 is preferably relatively small, the capacity of my fluid operated pump per stroke may be quite low, thus permitting my construction to be used where it is desirable to maintain the reciprocation of the motor piston and pump plunger at a relatively high rate and still afford only a relatively low production capacity from the device. It will also be apparent that with the construction illustrated, a fluid operated pump may be constructed having a relatively small external diameter. By this construction I am able to produce fluid operated pumps having an external diameter of less than one and one-quarter inches, which is substantially less than the minimum external diameter practical with fluid operated pumps of types well known in the prior art.

Although I have shown and described my construction in its preferred embodiment, it will be understood that certain parts and mechanisms thereof are the equivalent of other parts and mechanisms which may be substituted therefor without the exercise of invention, and that the size relationship between many of the parts thereof may be substantially varied without departing from the spirit of my invention, and I therefore intend to be afforded the full scope of the following claims.

I claim as my invention:

1. In a fluid operated well pump, the combination of: a column of fluid in a well under relatively high pressure; a column of fluid in a well under relatively low pressure; a motor cylinder having a motor piston therein having a fluid passage therethrough, the upper side of said motor piston being at all times in communication with said low pressure column through a pump outlet communicating between the upper end of said motor cylinder and said low pressure column; a pump cylinder having a pump piston therein having a fluid port therethrough; a travelling valve in said pump piston; a standing valve communicating with said pump cylinder below said pump piston; hollow connecting means operatively connecting said pistons and affording fluid communication between said fluid passage and said fluid port; a rod member attached to the upper end of said motor piston and extending into said high pressure column; means for connecting the other end of said motor piston with said high pressure column to admit operating fluid from said high pressure column to said other end of said motor piston to move the same in one direction; and means for connecting said other end of said motor piston with said low pressure column so as to equalize the fluid pressure on the ends of said motor piston, said motor piston thereupon being moved in the other direc-

tion by said rod member due to fluid pressure exerted on said rod member by said high pressure column.

2. In a fluid operated well pump, the combination of: a column of fluid in a well under relatively high pressure; a column of fluid in a well under relatively low pressure; a motor cylinder having a motor piston of relatively large diameter therein having a fluid passage therethrough, the upper side of said motor piston being at all times in communication with said low pressure column through a pump outlet communicating between the upper end of said motor cylinder and said low pressure column; a pump cylinder having a pump piston of relatively small diameter therein having a fluid port therethrough; a travelling valve in said pump piston; a standing valve communicating with said pump cylinder below said pump piston; hollow connecting means operatively connecting said pistons and affording fluid communication between said fluid passage and said fluid port; a rod member attached to the upper end of said motor piston and extending into said high pressure column; means for connecting the other end of said motor piston with said high pressure column to admit operating fluid from said high pressure column to said other end of said motor piston to move the same in one direction; and means for connecting said other end of said motor piston with said low pressure column so as to equalize the fluid pressure on the ends of said motor piston, said motor piston thereupon being moved in the other direction by said rod member due to fluid pressure exerted on said rod member by said high pressure column.

3. In a fluid operated pump, the combination of: a column of fluid in a well under relatively high pressure; a column of fluid in the well under relatively low pressure; a valve housing connected to said high pressure column; a motor cylinder connected to said valve housing therebelow and being in fluid communication with said low pressure column at all times through a pump outlet communicating between the upper end of said motor cylinder and said low pressure column; a motor piston in said motor cylinder having a passage therethrough communicating with the upper end of said motor cylinder; a pump cylinder connected relative to said motor cylinder and therebelow; a pump piston in said pump cylinder having a passage therethrough; hollow connecting means connecting said pistons and said passages; a rod member attached to the upper end of said motor piston and extending upwardly through said valve housing into said high pressure column; valve means in said valve housing for alternatively connecting the lower end of said motor piston with said high pressure column and with said low pressure column; and means operating in response to movement of said rod member to actuate said valve means.

4. In a fluid operated pump adapted to be operated in a well having a supply column of fluid at relatively high pressure and a production column of fluid at relatively low pressure, the combination of: a cylinder; piston means in said cylinder and having opposed ends of substantially equal areas; inlet means for admitting well fluid from the well to one end of said piston means; passage means providing fluid communication between said end of said piston means and the production column at all times; valve means adapted to open fluid communication between the other end of said piston means and

alternately the production column and the supply column; and piston rod means connected to said one end of said piston means and having an area exposed to the fluid pressure in said supply column when the said other end of said piston means is in fluid communication with said production column.

5. In a fluid operated pump adapted to be operated in a well having a supply column of fluid at relatively high pressure and a production column of fluid at relatively low pressure, the combination of: a cylinder; piston means in said cylinder and having opposed ends; inlet means for admitting well fluid from the well to one end of said piston means; passage means providing fluid communication between said end of said piston means and the production column at all times; valve means adapted to open fluid communication between the other end of said piston means and alternately the production column and the supply column; and piston rod means connected to said one end of said piston means and having an end exposed to the fluid pressure in said supply column when the said other end of said piston means is in fluid communication with said production column.

6. In a fluid operated pump adapted to be operated in a well having a supply column of fluid at relatively high pressure and a production column of fluid at relatively low pressure, the combination of: a cylinder; piston means in said cylinder and having opposed upper and lower ends; inlet means for admitting well fluid from the well to said upper end of said piston means; passage means providing fluid communication between said upper end of said piston means and the production column at all times; valve means adapted to open fluid communication between the lower end of said piston means and alternately the production column and the supply column; and piston rod means connected to said upper end of said piston means and having an area exposed to the fluid pressure in said supply column when the lower end of said piston means is in fluid communication with said production column.

7. In a fluid operated pump adapted to be operated in a well having a supply column of fluid at relatively high pressure and a production column of fluid at relatively low pressure, the combination of: a cylinder; piston means in said cylinder and having opposed ends; inlet means for admitting well fluid from the well to one end of said piston means; passage means providing fluid communication between said end of said piston means and the production column at all times; valve means above said cylinder and adapted to open fluid communication between the other end of said piston means and alternately the production column and the supply column; and piston rod means connected to said one end of said piston means and extending upwardly through said valve means, and having an upper end exposed to the fluid pressure in said supply column when the said other end of said piston means is in fluid communication with said production column.

8. In a fluid operated motor adapted to be operated from a supply column of fluid at relatively high pressure and having a low pressure discharge, the combination of: a cylinder; piston means in said cylinder; valve means adapted to

open fluid communication between one end of said piston means and alternately the low pressure discharge and the supply column, said piston means moving in said cylinder in one direction when communication is opened between said one end thereof and said supply column; passage means providing fluid communication between the other end of said piston means and said low pressure discharge; piston rod means connected to said piston means and having an end exposed to the high pressure fluid in said supply column so that when said one end of said piston means is in fluid communication with said low pressure discharge the fluid pressure exerted by said supply column on said piston rod means will cause it to move said piston means in said cylinder in a reverse direction; and means for connecting said piston rod means and said valve means constructed and arranged so that movement of said piston rod means controls the operation of said valve means.

9. In a fluid operated pump adapted to be operated in a well having a supply column of fluid at relatively high pressure and a production column of fluid at relatively low pressure, the combination of: a cylinder; a tubular member extending downwardly from the lower end of said cylinder and having an opening communicating with the fluid in the well; piston means in said cylinder and having a tubular sleeve extending downwardly therefrom into said tubular member and making a sliding fluid-tight fit therewith, there being a longitudinal passage through said sleeve and said piston communicating with the upper end of said cylinder; port means connecting the upper end of said cylinder with said production column; standing valve means in said tubular member; working valve means in said tubular sleeve; valve means for connecting alternately the lower end of said cylinder below said piston means with said production column and said supply column; and piston rod means connected to the upper end of said piston means and having an upper end exposed to the fluid pressure in said supply column.

10. In a fluid operated pump adapted to be operated in a well having a supply column of fluid at relatively high pressure and a production column of fluid at relatively low pressure, the combination of: a cylinder; a tubular member extending downwardly from the lower end of said cylinder and having an opening communicating with the fluid in the well; piston means in said cylinder and having a tubular sleeve extending downwardly therefrom into said tubular member and making a sliding fluid-tight fit therewith, there being a longitudinal passage through said sleeve and said piston communicating with the upper end of said cylinder, said piston means having upper and lower working ends of substantially equal area; port means connecting the upper end of said cylinder with said production column; standing valve means in said tubular member; working valve means in said tubular sleeve; valve means for connecting alternately the lower end of said cylinder below said piston means with said production column and said supply column; and piston rod means connected to the upper end of said piston means and having an upper end exposed to the fluid pressure in said supply column.

CLARENCE J. COBERLY.
